[57] CLAIM

The ornamental design for a vehicle rear view mirror, as shown and described.

DESCRIPTION

FIG. 1 is a front elevational view of a vehicle rear view mirror showing my new design;

FIG. 2 is a sectional bottom plan view thereof along line 2—2 in FIG. 1 looking in the direction of the arrows;

FIG. 3 is a side elevational view thereof;

FIG. 4 is a sectional bottom plan view thereof along a plane similar to line 2—2 in FIG. 1 and showing the mirror in an alternate position;

FIG. 5 is a sectional bottom plan view thereof along a plane similar to line 2—2 in FIG. 1 and showing the mirror in still another alternate position;

FIG. 6 is a front elevational view of a vehicle rear view mirror showing a second embodiment of my new design;

FIG. 7 is a sectional bottom plan view taken along line 7—7 in FIG. 6 looking in the direction of the arrows;

FIG. 8 is a fragmentary side elevational view of the second embodiment with the mirror in an alternate position; and

FIG. 9 is a fragmentary side elevational view of the second embodiment with the mirror in still another alternate position.

The mirror support has been broken away in FIGS. 8 and 9 for convenience of illustration.

The rear of the mirror is understood to be convex and unornamented.
